Patented Nov. 13, 1917.

UNITED STATES PATENT OFFICE.

CHARLES J. CLARKE, OF KINGSBURG, CALIFORNIA.

LANDSIDE-SHOE FOR PLOWS.

1,246,393.

Specification of Letters Patent.

Patented Nov. 13, 1917.

Application filed November 22, 1916. Serial No. 132,861.

To all whom it may concern:

Be it known that I, CHARLES J. CLARKE, a citizen of the United States, residing at Kingsburg, in the county of Fresno and 5 State of California, have invented certain new and useful Improvements in Landside-Shoes for Plows, of which the following is a specification, reference being had therein to the accompanying drawing.

10 My invention relates to improvements in landside shoes for plows, the primary object of which is to devise such a shoe which is applicable to the landside of a plow after the lower edge and heel thereof has become 15 so worn as to defeat its successful operation.

Another object of the present improvement is to construct the attaching means of the shoe, so that though the heel and lower edge of the landside may be badly worn, the 20 shoe will be correctly alined against the heel and lower edge of the landside and present a true working surface.

A further object of the present improvement is to construct a shoe which is simple 25 to apply, durable, and cheap to manufacture.

Other objects and advantages of the present improvement will be set forth in the following description and drawings, in which—

30 Figure 1 is a fragmentary perspective view of a turning plow showing my improved shoe applied to the landside thereof.

Fig. 2 is an enlarged fragmentary disassembled perspective view of the shoe and 35 showing its attachment to the heel of the landside.

Fig. 3 is a vertical sectional view taken on the line 3—3 of Fig. 1 and looking in the direction of the arrow.

40 Fig. 4 is a fragmentary perspective view of the front end of my improved shoe and showing its attachment means to the front end of the landside.

Fig. 5 is a reduced fragmentary perspective view of a landside shoe having an additional wearing surface along the outer edge thereof.

Referring now to the drawings in detail in which like reference numerals designate 50 similar parts throughout the several figures, 1, 2, 3 and 4 represent the body-portion, mold-board, plow-point and handles of a turning plow of the usual construction and well-known to those skilled in the art. A 55 landside 5 is attached to the body portion 1 of the plow in the usual manner. This

landside 5 is provided with a detachable face plate 6 having an obliquely cut rear end 7, which fits along the upper face of a triangular depressed portion 8, formed in the lower 60 edge of the rear end of the landside 5. Heretofore, the depressed portion 8 of the landside 5 is adapted to receive a detachable heel 8' a fragmentary portion of which is shown in Fig. 2. This heel is of a size and 65 shape to fit within the depression 8 in the landside 5 and may be removed when worn and a new one applied as is well known to those skilled in this art. It has been found heretofore, however, that when the heel has 70 become worn the entire lower edge 9 of the landside has also worn to such a degree that when a new heel is applied it will project below the worn edge of the landside and present a broken working surface which 75 seriously impairs the successful operation of the plow. To overcome these difficulties, I have constructed a landside shoe consisting of a narrow but thick plate 10, of a length sufficient to extend below the entire bottom 80 edge of the landside. A triangular-shaped portion 11 is made integral with the plate 10 and plumb with the outer edge thereof. This triangular portion 11 is adapted to fit against the lower edge 7 of the plate 6, and 85 within the triangular-shaped recess 8 in the landside 5. The other end of the plate 10 is provided with a vertical wedge-shaped flange 12 plumb with the inner edge of the plate and provided at its outer end with an 90 ear 13, having a slotted opening 14 there-through. The shoe is applied as follows: The plate is placed along the bottom of the landside 5, the triangular-shaped portion 11 fitting within the recess 8 in the landside 95 and secured thereto by means of a bolt (not shown) passing through registering openings 15 and 16 formed in the triangular portion 11 and recess 8 respectively. The wedge-shaped flange 12 and ear 13 is then 100 moved to lie against the inner face of the landside 5 and is secured thereto by means of a bolt 16 passing through the opening 14 in the ear 13 and through registering openings made in the landside and plate 6, there- 105 by fastening the rear part of the frog plate 21 of the plow, the plate 10, the outer end of the landside, and the outer end of the plate 6, together. Due to the slotted opening 14, the shoe may be adjusted vertically 110 to compensate for the wear along the bottom edge of the landside. The bolt 18 passing

through registering openings 19 and 20 secures the inner end of the landside 5 and plate 6 together. In some instances, where a greater wearing surface for the landside shoe is desired, a small elevated strengthening flange 22 is made along the outside top edge of the shoe extending from the front end of the shoe to the triangular portion 11, as is shown in Fig. 5.

10 Having thus described my invention, what I claim and desire to secure by Letters Patent is:

1. The combination with a plow landside having a removable face plate and a recess 15 adapted to receive a detachable heel, of a shoe comprising a member extending beneath the bottom edge of the landside, a member carried by one end thereof and fitting within the said recess in the landside, a 20 member carried by the other end of the shoe, and means for connecting the said member, removable face plate and landside together.

2. The combination with a plow landside, of a shoe attachable thereto, said shoe comprising a plate extending beneath the bottom edge of the landside, a triangular shaped member carried by one end of the plate and attachable to the front face of the heel of the landside, and an ear carried by 25 the other end thereof engaging the rear face of the landside and attachable thereto.

3. The combination with a plow landside,

of a shoe attachable thereto, said shoe comprising a plate extending below the bottom edge of the landside, a member carried by one end thereof and attachable to the front face of the heel of the landside, a wedge-shaped flange carried by the other end of the plate and engaging the inside of the landside, and an ear carried by the 40 wedge-shaped flange and providing means for attachment to the landside.

4. The combination with a plow landside, of a shoe attachable thereto, said shoe comprising a narrow plate extending beneath the bottom edge of the landside, a vertically extending member carried by one end thereof and attachable to the front face of the heel of the landside, and providing means for attaching the shoe to the landside, a wedge-shaped vertical flange carried by the rear end of the plate and engaging the inside of the landside, said wedge-shaped flange having its greatest width at the outer end of the plate, and an ear carried by the 50 said flange and providing means for attaching the shoe to the landside.

In testimony whereof I hereunto affix my signature in the presence of two witnesses.

CHARLES JACKSON CLARKE.
